UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 19,946, dated June 24, 1890.

Application filed April 15, 1890. Serial No. 348,105. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing, forming part thereof.

10 In the drawing is shown a side elevation of an umbrella or cane handle illustrating my new design.

A is the upwardly-extending body of the handle, and terminates on one side in the crook B and on the other side in the heel or pointed portion C, forming the recessed or depressed portion F in the upper part between the crook B and the heel C. The parts A B C are formed with horizontal grooves E, which

leave a series of parallel and horizontal ribs 20 extending entirely around the handle. The base D to the part A is an annular ornamented band. The upper part of the handle A B C is plain.

The handle is made of any suitable material.

Having now described my new design, what I claim as new, and desire to secure by Letters Patent, is—

25 The design for umbrella or cane handles, 30 substantially as herein described and shown.

In testimony of which invention I have hereunto set my hand.

HENRY O. SCHMIDT.
